BENDING MACHINE FOR PLYWOOD OR COMPOSITION BOARD

Emil C. Richter, St. Louis, Mo.

Application June 3, 1949, Serial No. 96,928

2 Claims. (Cl. 144—255)

1

This invention relates to bending machines, and more particularly to a bending machine adapted to bend sheet material such as plywood, composition board or the like into curved shapes.

A main object of the invention is to provide a novel and improved bending machine for sheet material which is very simple in construction, very easy to operate, and enabling sheet material such as plywood or the like to be bent into a great variety of curved shapes.

A further object of the invention is to provide an improved bending machine for bending sheet material such as plywood, composition board, and the like into curved shapes, said machine applying heat as well as bending pressure simultaneously to the sheet being bent, and being rugged in construction, inexpensive to fabricate, and requiring only a small amount of manual effort on the part of the operator.

Further objects and advantages of the invention will become apparent from the following description and claims, and from the accompanying drawings, wherein:

Figure 1 is a side elevational view of a sheet bending machine constructed in accordance with the present invention.

Figure 2 is a top plan view of the bending machine of Figure 1.

Figure 3 is an end elevational view of the bending machine of Figure 1.

Figure 4 is an enlarged cross sectional fragmentary detail view taken on line 4—4 of Figure 2.

Figure 5 is a cross sectional detail view similar to Figure 4 but showing the parts in positions at the end of a bending operation.

Figure 6 is an enlarged fragmentary cross sectional detail view taken on line 6—6 of Figure 3.

Referring to the drawings, 11 designates a rectangular table having a flat top 12 projecting laterally at one side of the table and having a laterally projecting bottom shelf 13. Secured to the end portions of the lateral projection of the table top 12 are upstanding bearing brackets 14, 14 in which is journaled a hollow shaft 15 having pulleys 16, 16 secured thereto adjacent its ends and located outwardly of the respective bearing brackets 14, 14. Rigidly secured to the shaft 15 inwardly adjacent the bearing brackets 14, 14 are respective radial arms 17, 17. Rigidly secured on the shaft 15 between the arms 17, 17 is an elongated hollow drum 18 having secured to its ends the respective gears 19, 19. Rigidly secured to the end portions of arms 17, 17 is a second hollow shaft 20 extending parallel to shaft 15

2

and having rotatably mounted thereon a hollow drum 21 coextensive in length with drum 18 and having gears 22, 22 secured to its ends meshing with the gears 19, 19. Rigidly secured to the end portions of shaft 20 are the respective crank handles 23, 23.

From Figure 3 it will be seen that the laterally projecting portion of table top 12 is substantially aligned with the space between drums 18 and 21. It will also be apparent that clockwise rotation of shaft 15 will cause arms 17, 17 to swing drum 21 clockwise around drum 18. It will also be seen that gears 22, 22 may be rotated counter-clockwise around shaft 20, as viewed in Figure 3, because of their meshing engagement with gears 19, 19, causing drum 21 to be also rotated counter-clockwise. As will be later explained, this provides an initial gripping action on a sheet of material inserted between the drums for bending.

Mounted on the laterally projecting portion of shelf 13 below the drums is a fluid pressure cylinder 24 having fluid pressure inlet conduits 25 and 26 connected to its end portions. Conduits 25 and 26 are connected to a suitable source of fluid pressure, not shown. The intermediate portion of the cylinder has an exhaust conduit 27 connected thereto. The pistons of the cylinder 24 are designated respectively at 28, 28. Connected to each piston 28 is a flexible cable 29 extending slidably and sealingly through an end wall of the cylinder. Each cable 29 extends over a pulley 30 rotatably mounted on the table leg below one of the pulleys 16 carried on shaft 15. Each cable 29 extends over a pulley 16 and is secured thereto. When fluid under pressure is introduced into the end portions of cylinder 24 through the conduits 25 and 26, the pistons 28, 28 are moved inwardly, providing tension in cables 29, 29, and causing shaft 15 to be rotated clockwise, as viewed in Figure 3. If a sheet of plywood, or other deformable sheet material is placed on the table top 12 and inserted between the drums 18 and 21, said sheet may be gripped by the drums by first rotating drum 21 counter-clockwise and then bent clockwise around drum 18 by introducing fluid under pressure into the end portions of cylinder 24. To facilitate the deformation of the sheet material, each drum contains a heater winding 31 connected through the hollow shaft on which the drum is mounted to a suitable source of voltage. The heat of the drums aids in softening the material for bending.

After the material is bent to the desired arcuate shape it may be released from between the

drums by rotating the hand cranks 23 counter-clockwise, as viewed in Figure 3, to their starting positions, wherein drum 21 underlies drum 18. The reverse rotation of drum 21 feeds the bent sheet material out from beneath drum 18 in a direction opposite to the direction of insertion.

Figure 4 shows the position of shafts 15 and 20 in starting position in full line view, and successive bending positions in dotted view. Figure 5 shows the relative positions of the shafts and drums in final bending position, the bent sheet of material being shown at 32. The bent sheet is finally released by manually rotating drum 21 clockwise.

While a specific embodiment of a bending machine for sheet material has been disclosed in the foregoing description, it will be understood that various modifications within the spirit of the invention may occur to those skilled in the art. Therefore it is intended that no limitations be placed on the invention except as defined by the scope of the appended claims.

What is claimed is:

1. A machine for bending deformable sheet material comprising a support having a horizontally disposed flat top, a shaft spaced above said flat top and mounted on said support for rotary movement about a first horizontal axis, a first drum circumscribed about said first shaft and secured axially thereof, an arm projecting radially of said shaft contiguous to each end thereof and secured thereto, a second drum positioned intermediate said arms and mounted therebetween for rotary movement about a second horizontal axis spaced from said first horizontal axis, the spacing between said first and second horizontal axes being selected to provide a space contiguous to said flat top for the extension therethrough of the sheet material to be deformed, means operatively connecting said second drum to said first drum for rotary movement about said second horizontal axis in response to the rotary movement of the assembly of said shaft and said first drum about said first horizontal axis, and actuating means carried by said support and operatively connected to said shaft for effecting the rotary movement of the latter, whereby the sheet of material inserted between said drums will be arcuately bent, said actuating means comprising a fluid pressure cylinder disposed longitudinally of said support and secured thereto, a piston disposed in said cylinder and mounted for sliding movement toward and away from one end thereof, a first pulley circumscribed about said shaft and secured thereto, a second pulley disposed adjacent to and spaced from said one end of said cylinder and mounted on said frame for rotary movement about a third horizontal axis transverse of said first and second named horizontal axes, and a flexible cable guidingly supported on said second pulley and having one end trained about said first pulley and secured thereto and

having the other end operatively connected to said piston, whereby said second drum will be rotated about said second horizontal axis and said first drum responsive to the admission of fluid under pressure to said cylinder.

2. A machine for bending deformable sheet material comprising a support having a horizontally disposed flat top, a shaft spaced above said flat top and mounted on said support for rotary movement about a first horizontal axis, a first drum circumscribed about said first shaft and secured axially thereof, an arm projecting radially of said shaft contiguous to each end thereof and secured thereto, a second drum positioned intermediate said arms and mounted therebetween for rotary movement about a second horizontal axis spaced from said first horizontal axis, the spacing between said first and second horizontal axes being selected to provide a space contiguous to said flat top for the extension therethrough of the sheet material to be deformed, means operatively connecting said second drum to said first drum for rotary movement about said second horizontal axis in response to the rotary movement of the assembly of said shaft and said first drum about said first horizontal axis, actuating means carried by said support and operatively connected to said shaft for effecting the rotary movement of the latter, whereby the sheet of material inserted between said drums will be arcuately bent, said actuating means comprising a fluid pressure cylinder disposed longitudinally of said support and secured thereto, a piston disposed in said cylinder and mounted for sliding movement toward and away from one end thereof, a first pulley circumscribed about said shaft and secured thereto, a second pulley disposed adjacent to and spaced from said one end of said cylinder and mounted on said frame for rotary movement about a third horizontal axis transverse of said first and second named horizontal axes, and a flexible cable guidingly supported on said second pulley and having one end trained about said first pulley and secured thereto and having the other end operatively connected to said piston, whereby said second drum will be rotated about said second horizontal axis and said first drum responsive to the admission of fluid under pressure to said cylinder, and heater means carried within each of said drums and adapted to be connected to a source of electrical energy.
